United States Patent Office.

JOHN A. EVARTS, OF WEST MERIDEN, CONNECTICUT, ASSIGNOR TO BRADLEY AND HUBBARD, OF SAME PLACE.

Letters Patent No. 73,706, dated January 28, 1868.

IMPROVEMENT IN MATCH-SAFE.

The Schedule referred to in these Letters Patent and making part of the same.

TO ALL WHOM IT MAY CONCERN:

Be it known that I, JOHN A. EVARTS, of West Meriden, in the county of New Haven, and State of Connecticut, have invented a new Improvement in Cast-Metal Match-Safes, &c.; and I do hereby declare the following, when taken in connection with the accompanying drawings, and the letters of reference marked thereon, to be a full, clear, and exact description of the same, and which said drawings constitute part of this specification, and represent, in—

Figure 1, a perspective view.

Figure 2, a perspective view of the one part.

Figure 3, a perspective view of the other part; and in

Figure 4, a sectional view on line xx .

This invention relates to an improvement in the construction of receptacles for matches, designed to be hung or secured to the wall, and consists in a base or back, and a front, both formed from cast metal, the front cast with lugs, and placed in a mould, and in the mould the back or base is cast thereon, attaching itself to the front by the process of casting, by means of the lugs on the front.

To enable others to construct my improvement, I will proceed to describe the same, as illustrated in the accompanying drawings.

A is the case, and B the back. I first form a pattern of the form of the case A, or other desired similar form, having upon the edge one or more projecting lugs, a , then mould and cast the part A in the usual manner; then mould the part B, placing the part A in its proper position on the pattern, filling with sand around the part A on to the pattern B; then remove the pattern B from the sand, leaving the part A therein, and close the flask, and pour in the metal, which flows around the lugs a , and, cooling, attaches itself securely to the part A, as seen in figs. 1 and 4, which, removed from the sand, the case or safe is complete. Thus is formed, in the simplest and cheapest possible manner, a neat and durable match-safe.

In forming the lugs upon the one part of the case, care should be taken that they be of such form that the other part, being cast thereon, will lock itself thereto, as seen in fig. 4. As many lugs should be used as are necessary for the security of the parts.

Having thus fully described my invention, what I claim as new and useful, and desire to secure by Letters Patent, is—

The match-safe herein described, consisting of the front and back, constructed from cast metal, and the two parts united in the manner described, as a new article of manufacture.

JOHN A. EVARTS.
